CLAIM

The ornamental design for a vaporizer charger, as shown and described.

DESCRIPTION

FIG. 1 is a perspective view of a vaporizer charger, showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the selected portion in FIG. 2. The broken lines in the figures illustrate portions of the vaporizer charger that form no part of the claimed design; and

The additional dot-dot-dash lines surrounding the detail in FIGS. 2 and 8 are for annotative purposes only and form no part thereof.
